ARTIFICIAL HAND

Carl Lohmann, New York, N. Y.

Application January 14, 1948, Serial No. 2,182

5 Claims. (Cl. 3—12)

1

This invention relates to new and useful improvements in artificial limb constructions, and, more particularly, aims to provide a novel and valuable artificial hand.

According to the present invention, ball and socket joints are provided at the knuckle locations, arranged so that any one or more of the fingers may be variously adjusted as desired and so that when thus adjusted they will remain in their adjusted positions. Preferably, detent means are partially carried by each of the ball and socket elements of a joint, and means are present for limiting relative movement of the parts at the joint, to restrain swinging movement of one part of a joint relative to another part of that joint in such manner that said swinging is always a rotative one about a single axis.

Members simulating the bones of a human finger and the bone at the root of the finger of the human hand are provided, between which members said joints are interposed. Said members are shaped to provide top channels extending lengthwise of the members, these channels specially shaped for coaction with an endwise movable member, preferably a long leaf spring resiliently biased to longitudinal curvature. The means provided by this spring and said channels is effective to curl or bend inward, toward the palm of the hand, the finger served by said means, or each of as many fingers as are so served, when, in regard to its associated finger, said spring is endwise advanced to traverse all the channels one after another.

As the invention is herein shown and described, said spring is always partially inserted into the hand, that is, under the skin-simulating sheath thereof, and into the channel of that one of the bone members of the associated finger corresponding to the phalange of a natural finger at the inner end of the latter. In rear of such entry of the spring into the hand, the spring extends along the back of the hand and is housed in a guiding and holding track preferably having a substantially flat bottom. With the one or more springs in retracted position, that is, only partially inserted into the hand as above, the fingers of the artificial hand can be manually adjusted as desired, as by the use of the other hand. When a spring is endwise advanced, by use of the other hand, the finger associated with that spring is completely curled or bent inward toward the palm of the artificial hand, as for grasping an article.

For further comprehension of the invention, and of the objects and advantages thereof, ref-

erence will be had to the following description and accompanying drawing, and to the appended claims in which the various novel features of the invention are more particularly set forth.

5 In the accompanying drawing forming a material part of this disclosure:

Fig. 1 is a view, partially in side elevation and partially in section, showing in full lines the wrist portion and a straight extended finger of 10 an artificial hand pursuant to the invention, also outlining in dot and dash other parts of said hand.

Fig. 2 is a detail sectional view, taken on the line 2—2 of Fig. 1.

15 Fig. 3 is a detailed sectional view, taken on the line 3—3 of Fig. 1.

Fig. 4 is a view similar to Fig. 1, but showing said finger bent at its knuckle locations to curl inward toward the palm of the hand, for grasping an article.

20 Fig. 5 is a perspective view of the spring, per se.

Fig. 6 shows in perspective one of the ball and socket carrying members which extend between knuckle and knuckle of said finger.

25 Fig. 7 is an enlarged sectional view, showing one of the ball and socket joints.

The artificial hand, according to the present invention, includes a plurality of flexible fingers; however, the details of the construction are illustrated in connection with the index finger 17 only. It is to be understood that those constructional details apply equally well to each of the other fingers of the artificial hand; such as the finger 15 and the thumb 16, shown in dot and dash lines in Fig. 1.

30 The index finger 17 includes a sheathing 18 for simulating the skin of the human hand, within which sheathing are articulated bone members 19, 20, 21 and 22, made of aluminum, plastic or some other suitable and preferably light and strong material, for simulating the equivalent bones of the human index finger.

35 The bone member 19 is shown as extended at 19' to form a part of the wrist and also to back up the relatively stiff padding or other filler, not shown, for shaping the sheathing 18 at the palm of the hand.

The bone member 19 at its forward end carries a spherical socket 23 within which is pivotally but irremovably seated a ball 24 formed at the rear end of the bone member 20. The bone member 20 at its forward end carries a spherical socket 25 within which is pivotally but irremovably seated a ball 26 formed at the rear end 50 of the bone member 21. The bone member 21

at its forward end carries a spherical socket 27 within which is pivotally but irremovably seated a ball 28 formed at the rear end of the bone member 22. These ball and socket joints between the bone members thus represent the knuckles of the finger of the human hand. The balls are irremovable from their sockets because the sockets have their rims in a plane marking off slightly more than one-half the bulk of the associated balls in any possible angular dis-
position of the ball relative to its socket.

Means is provided to prevent lateral pivoting of the balls in their respective sockets and so limit the ball members 20, 21 or 22 to swing vertically up and down, or toward and away from the palm of the hand. Referring in this connection particularly to Figs. 6 and 7, where, in order not unduly to add to the drawings, the arrangement provided for each of the ball and socket joints is shown only in connection with the joint between the bone members 20 and 21, the socket 25 has an arcuate keyway 29 within which is endwisely slidable an arcuate key 30 fixedly carried by the ball 28.

In order to permit the bone member 21 to be releasably held in any one of a plurality of adjusted positions on the bone member 20, a detent means is provided. The detent means comprises an arcuate line of recesses 31 formed in the socket 25 as a prolongation of the keyway 29. A small ball 32 for engaging any one of the recesses 31 aligned with the ball is projected from a well 34 in the ball 28 by a light spring 33. A precisely similar arrangement is provided in connection with the ball and socket joints 23-24 and 21-20; but preferably, however, with the recesses corresponding to the recesses 31 provided for the socket 27 to a less number than said recesses as provided for the socket 25 and for the socket 23.

The under portions of the bone members 20, 21 and 22 are suitably shaped by fillers 35 of dense padding formed of sponge rubber or the like material. To allow bending of the finger, as from the condition shown in Fig. 1 to that shown in Fig. 4, the sheathing 18 should be somewhat elastically stretchable along the length of the finger, particularly between filler blocks 36, 37, 38 and 39, which are formed of aluminum, plastic or the like. The filler blocks have the cross section illustrated in Fig. 3 in the case of the block 36 for assisting in giving the artificial finger a natural lateral roundness at its upper portions.

These blocks overlie and close intermediate portions of channels extended along the tops of the members 19, 20, 21 and 22. All of the channels are of the same width, about the width indicated in Fig. 3 for the channel 40 of the bone member 19.

As will be noted, the channel 40, from the point 41, where said channel has an end aligned with an opening in the sheathing 18, has its bottom extending forwardly substantially along a straight line, until such bottom downwardly curvilinearly dips at 42, to correspondingly variously deepen said channel. Also as will be noted, the channel 43 along the top of the bone member 20 has its bottom, starting from the rear end of said member, first curvilinearly rising and then curvilinearly descending, according to a somewhat symmetrical convexity, to correspondingly variously deepen said channel. Also as will be noted, the channel 44 along the top of the bone member 21 has its bottom, starting from

the rear end of the channel, first rising according to a straight line slope to a convexly curved crest and then continuing as a curvilinearly descending final portion, to correspondingly deepen the channel, as shown very clearly in Fig. 6.

As will further be noted, the channel 45 along the top of the bone member 22 has a first generally curvilinearly rising bottom and then a straight bottom terminated by an end wall 46.

It should also be noted that with the parts as in Fig. 1, the rear end of the channel 43 at its bottom is at a lower point than the forward end of the bottom of the channel 40, and that the rear end of the channel 44 at its bottom is at a lower point than the forward end of the channel 43 at its bottom, and that the rear end of the channel 45 at its bottom is at a lower point than the highest point of the bottom convexity of the channel 44.

The channel features just described, assisted by the smooth under sides of the blocks 36, 37, 38 and 39, where said blocks overlie the channels, allow a single long leaf spring 47, normally having its forward portion in substantially the entirety of the channel 44, to be endwisely forwardly moved, first to enter and pass through the channel 43, next to enter and pass through the channel 44, and next to enter and pass all along the channel 45 until the forward end of said spring abuts against the end wall 46.

The spring 47 is resiliently set so as to resiliently assume a curvilinear line of lengthwise extension, as shown in Fig. 5. The resilient bias of the spring is such that, incidental to sending of the spring into the channels 43-45 as just explained, the members 20, 21 and 22 are forced, despite the presence of the elements 31-34 at the ball and socket joints 24-26 and the presence of corresponding elements at the other ball and socket joints, to the redispositions shown in Fig. 4 from those shown in Fig. 1. Nevertheless, the resilient bias of said spring is not such as to make the spring so stiff that, when withdrawn to the extent shown in Fig. 1 for full normal return into a storage track 48 having the cross section shown in Fig. 2, and having its bottom straight, the spring cannot easily be drawn to flat condition throughout that portion of its length withdrawn from the finger 17 for housing in said track.

The track 48 is suitably secured to the back of the hand, in line with the channel 40. The length of that part of the spring housed in the track 48 when the former is retracted to the extent shown in Fig. 1 is diagrammatically indicated in Fig. 5 as extending between a terminal upturned lip 49 on the spring and the dot and dash line 50.

The lip 49 may have a string or cord 51 connected thereto by way of an aperture 52 therethrough, for retracting the spring, to allow the hand to be arranged as in Fig. 1. The spring is also shown as carrying a handle projection 53, so that by use of the other hand to grip the projection the spring may be extended into the artificial finger, to cause the finger 17 to be arranged as in Fig. 4. Such projection can also be used to retract the spring, whereupon the finger 17 may be rearranged as in Fig. 1 by pressing the tip of the finger to a table top or the like.

The elements 31-34 may be omitted, or retained for holding the finger 17 as directly manually adjusted as above explained; in which latter connection it will be understood that such

connection it will be understood that such

finger adjustment will be done when the spring 47 is retracted as shown in Fig. 4.

The artificial hand of the present invention can be made very natural in appearance, in any arrangement of the fingers, each is provided with a simulated fingernail 54 set in and suitably secured to and exposed through the sheathing 18.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. In an artificial hand, a plurality of elongated bone members arranged in end alignment and simulating the bones of one of the fingers of the human hand and the bone of the human hand at the root of the said finger, sockets formed at the front ends of each of said bone members except the bone member simulating the bone at the tip of the finger of the human hand, balls formed at the rear ends of each of said bone members except the bone member simulating the bone at the root of the finger of the human hand, the balls of the bone members being pivotally engaged in the sockets of the next adjoining bone members, means limiting pivoting of said bone members relative to each other to a plane extended at right angles to the plane of the palm of the hand, said bone members being formed along their tops with end aligned channels, means removably inserted into said channels for holding said bone members pivoted relative to each other toward the palm of the hand, and means for individually holding each of said bone members in a desired pivoted position relative to its adjacent bone member when said removable means is withdrawn from said channels.

2. In an artificial hand, a plurality of elongated bone members arranged in end alignment and simulating the bones of one of the fingers of the human hand and the bone of the human hand at the root of the said finger, sockets formed at the front ends of each of said bone members except the bone member simulating the bone at the tip of the finger of the human hand, balls formed at the rear ends of each of said bone members except the bone member simulating the bone at the root of the finger of the human hand, the balls of the bone members being pivotally engaged in the sockets of the next adjoining bone members, means limiting pivoting of said bone members relative to each other to a plane extended at right angles to the plane of the palm of the hand, said bone members being formed along their tops with end aligned channels, means removably inserted into said channels for holding said bone members pivoted relative to each other toward the palm of the hand, and means for individually holding each of said bone members in a desired pivoted position relative to its adjacent bone member when said removable means is withdrawn from said channels, said pivot limiting means comprising a key formed on each of said balls, and the material of said bone members forming said sockets being formed with keyways into which said keys are slidably extended.

3. In an artificial hand, a plurality of elongated bone members arranged in end alignment and simulating the bones of one of the fingers

of the human hand and the bone of the human hand at the root of the said finger, sockets formed at the front ends of each of said bone members except the bone member simulating the bone at the tip of the finger of the human hand, balls formed at the rear ends of each of said bone members except the bone member simulating the bone at the root of the finger of the human hand, the balls of the bone members being pivotally engaged in the sockets of the next adjoining bone members, means limiting pivoting of said bone members relative to each other to a plane extended at right angles to the plane of the palm of the hand, said bone members being formed along their tops with end aligned channels, means removably inserted into said channels for holding said bone members pivoted relative to each other toward the palm of the hand, and means for individually holding each of said bone members in a desired pivoted position relative to its adjacent bone member when said removable means is withdrawn from said channels, said first-mentioned holding means comprising an elongated flexible spring extended into said grooves, said spring having a set to assume a curved shape for holding said bone members pivoted relative to each other toward the palm of the hand.

4. In an artificial hand, a plurality of elongated bone members arranged in end alignment and simulating the bones of one of the fingers of the human hand and the bone of the human hand at the root of the said finger, sockets formed at the front ends of each of said bone members except the bone member simulating the bone at the tip of the finger of the human hand, balls formed at the rear ends of each of said bone members except the bone member simulating the bone at the root of the finger of the human hand, the balls of the bone members being pivotally engaged in the sockets of the next adjoining bone members, means limiting pivoting of said bone members relative to each other to a plane extended at right angles to the plane of the palm of the hand, said bone members being formed along their tops with end aligned channels, means removably inserted into said channels for holding said bone members pivoted relative to each other toward the palm of the hand, and means for individually holding each of said bone members in a desired pivoted position relative to its adjacent bone member when said removable means is withdrawn from said channels, said first-mentioned holding means comprising an elongated flexible spring extended into said grooves, said spring having a set to assume a curved shape for holding said bone members pivoted relative to each other toward the palm of the hand, and a track mounted along the top of the bone member simulating the bone at the root of the finger of the human hand to receive and retain said spring when withdrawn from said channels.

5. In an artificial hand, a plurality of elongated bone members arranged in end alignment and simulating the bones of one of the fingers of the human hand and the bone of the human hand at the root of the said finger, sockets formed at the front ends of each of said bone members except the bone member simulating the bone at the tip of the finger of the human hand, balls formed at the rear ends of each of said bone members except the bone member simulating the bone at the root of the finger of the human hand, the balls of the bone members being pivotally

engaged in the sockets of the next adjoining bone members, means limiting pivoting of said bone members relative to each other to a plane extended at right angles to the plane of the palm of the hand, said bone members being formed along their tops with end aligned channels, means removably inserted into said channels for holding said bone members pivoted relative to each other toward the palm of the hand, and means for individually holding each of said bone members in a desired pivoted position relative to its adjacent bone member when said removable means is withdrawn from said channels, the material of said bone members defining said sockets being formed with a series of recesses arranged in a line extended parallel to the plane in which said bone members are limited to pivot, and a spring pressed ball mounted on said balls and selectively engageable with said sockets in the pivoted positions of

said bone members forming said latter-mentioned holding means.
